UNITED STATES PATENT OFFICE.

JAMES W. IVORY, OF PHILADELPHIA, PENNSYLVANIA.

PROTECTOR AND GUIDE-SHEATH FOR NAIL-FILES.

1,367,975.

Specification of Letters Patent.

Patented Feb. 8, 1921.

Application filed November 10, 1919. Serial No. 336,963.

To all whom it may concern:

Be it known that I, JAMES W. IVORY, a subject of the King of Great Britain, residing in the city and county of Philadelphia, 5 State of Pennsylvania, have invented a new and useful Protector and Guide-Sheath for Nail-Files, of which the following is a specification.

My invention consists in providing a nail 10 file with a protector and guide sheath therefor, the construction of the same and advantages of the same being hereinafter described, and the novel features thereof pointed out in the claims that follow the specification.

15 The invention is satisfactorily illustrated in the accompanying drawing, but the important instrumentalities thereof may be varied, and so it is to be understood that the invention is not limited to the specific details 20 shown and described, as long as they are within the spirit or scope of the claims.

Figures 1 and 2 represent views of opposite faces of the protector and guide sheath embodying my invention, the same including 25 a file to which the device is applied.

Fig. 3 represents a longitudinal section thereof on line 3—3 Fig. 1.

Fig. 4 represents a face view of the sheath itself.

30 Figs. 5, 6, and 7 represent transverse sections thereof on lines respectively 5—5, 6—6 and 7—7 Fig. 1.

Figs. 8, 9, 10 and 11 represent other embodiments of my invention.

35 Similar numerals of reference indicate corresponding parts in the figures.

Referring to the drawings,

1 designates a nail file which excepting the features of my invention applied thereto 40 is of well known form.

2 designates a sheath, the same consisting of the pointed plate 3 of suitable piece of metal, horn, celluloid, or other suitable material, having on its sides in the longitudinal 45 direction thereof the flanges 4 which extend at an angle from said sides, thus forming in a measure a channel in which the file is seated, the file frictionally engaging the inner walls of said flanges and so retaining its

50 position on the sheath, this being assisted by the lips 5 which are inturned from proper portions of the flanges 4 and overhang the file thereat, as most plainly shown in Fig. 1.

In the face of the file near the point 6 55 of the sheath are the tapering or beveled grooves or channels 7 which lead to the inner

sides of the adjacent portions of the flanges 4 and serve to guide the nail to said portions, either of said grooves or channels being adapted to receive the edge of a nail for that 60 purpose.

The sheath in Figs. 1, 2, 3, and 4 is extended beyond the head end of the file forming the handle 8 for operating the device, while in Fig. 8, the handle is of increased 65 length providing a greater grasping surface.

The end of the file at the point portion of the sheath has the slope 9 thereon, the same serving to guide the nail from said portion to the adjacent surface of the file.

70 In Fig. 9, a point section 10 of horn, hard rubber, etc., continuous of the relative end of a short file is riveted or otherwise secured firmly to the sheath. Continuous of the other end of the file is the auxiliary handle 75 section 11 which is seated on the sheath and retained in position by the flanges 4 and lips 5 and serving to strengthen the portion of the sheath to which said section 11 is applied.

80 It will be seen that the flanges 4 are of a height equal to the thickness of the file and extend above the face of the latter, the extended portions having their inner walls or faces beveled, or they may be semi-rounded, 85 said flanges being on opposite sides of the sheath.

It will be seen also that in the use of the device the flanges 4 give the angle that the file should have as it engages the nail, so that 90 the file will not cut the nail on a perpendicular line but slightly under corresponding to the angle of the bevel of the guide flanges which latter act as a shield to protect the soft tissues or quick sensitive fibers 95 of connective tissues and delicate skin fibers from the edges of the teeth of the file, as said flanges on the shield stand in the way so that the edges of the file cannot come in contact with these soft tissues beneath the 100 nail.

The grooves or channels 7 facilitate the entrance of the free end of the nail to the file, the flanges taking the same bevel as the side flanges so as to be readily applied to 105 the corners of the nail to be filed.

The point of the sheath which extends beyond the file is for cleansing beneath the nail, and the handle portion 8 having its outer end rounded is adapted as a cuticle pusher, the 110 same being true of the corresponding end of the handle section 11.

The point section 10 extends beyond the end of the sheath and takes the place of the point 6 of the latter as a cleanser beneath a nail, and it is cut away on its side borders 5 so as not to interfere with the nail in its passage on the edge of the sheath, the flanges of the latter extending above the cut away borders of said section 10, the same being true of the handle section 11, and this latter 10 section may also serve as a cuticle pusher.

If desired, the flanges 4 may be beveled inwardly so as to take hold of the file, in which case the file may be fitted into the sheath by sliding it on the plate or back 2 15 of the sheath through the lips 5 and between the beveled flanges, whereby the sheath is firmly connected with the file and the latter may be readily removed from the sheath by drawing it out of the same.

20 In Figs. 10 and 11 I show the point portion of the file somewhat twisted or spiral, so as to cleanse both the nail and the flesh at one operation, and also adapting the points for cleansing in reverse order as the file is 25 applied to the right hand, to the left, and vice versa.

Having thus described my invention what I claim as new and desire to secure by Letters Patent, is:—

30 1. A sheath for a nail file consisting of a plate having on the sides thereof flanges extending therefrom, said plate being adapted to have a file endwise insertible therein and seated thereon, and by said flanges to engage the sides of the file, the space between said 35 flanges being tapered lengthwise of the plate.

2. A sheath for a nail file consisting of a plate having on the sides thereof flanges extending therefrom, said plate being adapted 40 to have a file endwise insertible therein and seated thereon, and said flanges to engage the sides of the file, the space between said flanges being tapered lengthwise of the plate, and lips inturned from the flanges adapted 45 to overhang the face of the file.

3. A sheath for a nail file consisting of a pointed plate having on the sides thereof flanges extending angularly therefrom, the file being adapted to be inserted endwise 50 therein and to be seated on said plate and engaged by said flanges, the file having therein adjacent to its point channels leading to said flanges.

4. A sheath for a nail file consisting of a

plate having flanges on its sides, said plate 55 being adapted to have the file endwise insertible therein and seated thereon and have said flanges engage the sides of the file, the space between said flanges being tapered lengthwise of the plate, a terminal of the 60 sheath extending from the terminal of the file being adapted to form a handle and a cuticle pusher.

5. A sheath for a nail file consisting of a plate having flanges on its sides, said plate 65 being adapted to have the file endwise insertible therein and seated thereon, and said flanges to engage the sides of the file, a point at one end of said sheath, and a file at the point portion of the sheath having a slope 70 thereon.

6. A sheath for a nail file consisting of a plate having flanges on its sides, said plate being adapted to have the file endwise insertible therein and seated thereon, and said 75 flanges to engage the sides of the file, a point at one end of said sheath, and a handle and cuticle pusher on the other end, and a file at the point portion of the sheath having a slope 80 thereon.

7. A sheath having flanges on its sides and having a point at one end, and a file endwise insertible therein and adapted to be seated on said sheath and embraced by said flanges and having on its face near its point 85 portion a slope or bevel leading to said flanges.

8. A sheath for a nail file having a point portion of spiral or twisted form extended 90 beyond the end of the file.

9. A sheath pointed at one end and having side flanges and bendable lips on said flanges, and a file between said flanges with said lips bent thereover, said file having in its face near the point grooves beveled upon opposite sides toward said flanges.

10. A sheath pointed at one end and having side flanges and bendable lips on said flanges, and a file between said flanges with said lips bent thereover, said file having in 100 its face near the point grooves beveled upon opposite sides toward said flanges, the inner faces of the adjacent portions of the flanges being correspondingly beveled.

JAMES W. IVORY.
